INDIVIDUAL TUMBLER HOLDER AND RACK
EMBODYING THE SAME

Adolph J. Havlis, Oak Park, Ill., assignor, by mesne assignments, to Adolph J. Havlis, Frank Havlis, Albert F. Havlis, Albina Zderad, and Stanley P. Dyba, copartners doing business as Keystone Metal Products Company, a limited partnership

Application August 30, 1939, Serial No. 292,583

2 Claims. (Cl. 211—74)

This invention relates to tumbler racks and similar articles and has to do particularly with improvements in the construction of wire tumbler racks.

One of the main objects of the invention is to provide an improved individual wire tumbler or glass holder of such form that when applied to any suitable base it will provide complete individual retention for the tumbler or glass without securing additional members to the front of the holder for closing the same against displacement of the tumbler therefrom and without the use of dividers, spacers or the like common to a plurality of tumblers or glasses.

Another object of the invention is to provide an improved tumbler rack having tumbler or glass holders of the character above set forth for individually holding the glasses or tumblers in separated and individual relation; also against undue relative movement and impact with each other such as occurs where dividers or spacers are employed to form tumbler receiving compartments.

It is also an object of the invention to provide an individual wire tumbler or glass holder and a tumbler rack embodying such holders, which holders and the rack comprising the same are of simple and inexpensive construction and of pleasing appearance; also an individual wire tumbler or glass holder formed of a single generally U-shaped wire and a rack embodying such holders which is composed of relatively few parts adapted to be conveniently assembled and brought to form.

Another object of the invention is to provide an improved method of making the individual tumbler holders and rack of the character described.

Further objects and advantages of the invention will appear from the following detailed description taken in connection with the accompanying drawings, in which:

Figure 1 is a top plan view of a tumbler rack embodying the present invention;

Figure 2 is a side view of the rack shown in Figure 1;

Figure 3 is a bottom plan view showing, in the flat, the supporting rings constituting the base of the particular rack selected for illustration and the individual tumbler or glass holders as applied thereto;

Figure 4 is a view showing, in the flat, one of the individual tumbler or glass holders;

Figure 5 is a fragmentary perspective view showing one of the individual tumbler or glass holders applied to a suitable base and after bringing the tumbler or glass holder to form;

Figure 6 is a view showing, in the flat, another form of tumbler or glass holder embodying the present invention;

Figure 7 is a front view of the individual tumbler or glass holder shown in Figure 6, showing the same applied to a suitable base and after being brought to form; and

Figure 8 is a side view showing a slightly modified form of holder embodying the present invention.

Referring now in detail to the drawings, the particular rack selected for illustration comprises 10 a base consisting of two concentric wire rings 10 and 11. The base which determines the shape of the rack is shown of round or circular form, but it is to be understood that it may be of square, rectangular, octagonal, or of any other suitable or preferred form.

It is to be further understood that the base may be of stepped construction to support the tumblers or glasses at different elevations, somewhat along the line shown in my design Patent 20 No. D-114,387, issued April 18, 1939, and that a wide range of other modifications are contemplated within the scope of the present invention.

The individual tumbler or glass holders 12 are formed of wire of suitable gauge and, in the flat, 25 are of generally U-shaped form, with the sides or legs of the U contracted or pressed or drawn inwardly toward each other at 14 for an important purpose which will presently appear. The connecting portions between the legs of the 30 U-shaped members are rounded as shown at 15, but this may vary within the scope of the invention.

Where the base is of the character shown in the drawings, the ends 16 and 17 of the wire base 35 rings are preferably not welded or otherwise secured together but are merely brought into abutting relation, being held together by the tumbler or glass holders 12, although this, too, may vary.

In forming the rack the wire base rings 10 and 40 11 are placed, for example, in a jig in the desired concentric relation. The jig is preferably grooved or formed to receive and hold the rings 10 and 11 in the desired relation, and is also preferably grooved or formed to receive and hold, in the flat, the generally U-shaped tumbler holders 12, with the free ends 18 of the legs thereof extending across and disposed on the rings 10 and 11 as shown in Figure 3. Then, with all of the holders 12 in position upon the base rings 10 and 11 as shown in Figure 3, the free ends 18 of the legs of the holders 12 are 50 welded to the wire rings 10 and 11 at 20. The welding of all of the holders to the base of the rack at the points 20 is preferably accomplished by a single welding operation. By welding the ends 18 of one tumbler holder 12 to opposite sides of each joint 16 and 17, the ends of the rings 10 and 11 are held together without welding the same.

60 The glass holders 12 are then rolled over a

suitable fixture, die, or jig to bring the outer rounded ends 15 into position above and as shown in Figures 2 and 5 into position substantially parallel to the ends 18 and to the plane of the rings 10 and 11, and to give the intermediate contracted sides 14 of the holders an outwardly rolled and generally rounded form as shown. The outer rounded ends 15 are not only brought into position substantially parallel to the ends 18 of the holders and to the plane of the rings 10 and 11, but are positioned over the base rings 10 and 11 substantially as shown in plan in Figure 1.

If desired, the rolled formation of the intermediate sides 14 of the holders may be continued along the rounded ends 15 instead of having the ends of generally flat or planar form as shown in Figure 5. This is indicated in side elevation at 15' in Figure 3, the other portions of this holder being indicated by primed reference characters similar to the reference characters applied to Figures 1 through 5.

The rolling of the intermediate portions of the individual holders 12 not only positions the looped glass receiving ends 15 so that the glasses may be placed therein with their lower ends on the base of the rack as indicated in dotted lines at 30 in Figures 2 and 5, but the contracted sides 14 when thus brought to form provide complete individual retention for the glass without securing additional members to the front of the holder to close the same against displacement of the glass from the holder and without the use of dividers, spacers, or the like common to a plurality of tumblers or glasses. This is an important aspect of the present invention.

Moreover, the individual tumbler holders of the type described are adapted to a wide variety of rack structures and permit a wide range of changes in the design and construction of the other parts of the rack. Where dividers or spacers are employed to form tumbler or glass receiving compartments, the same range of variation in the design and construction of the rack has not been possible. The individual holders 12 each consisting of a single piece of wire, the cost is reduced and assembly is simplified. With the contracted sides 14, the desired retention is formed by the rolling operation which brings the looped end 15 and the ends 18 to the desired positions. Instead of a rolling operation on the intermediate portions of the holders 12 as described, these holders may be brought to form in any other suitable or desired manner, and what are described as the rolled intermediate and retention forming portions of the holders 12, instead of being rounded as shown, may be of any other desired shape.

In use, each holder 12 individually supports a glass or tumbler as indicated at 30. The glasses 30 are thus held in separated and individual relation; also against undue relative movement and against impact with each other. The holders 12 are preferably formed of hard wire with enough temper—that is, with enough springiness—firmly to support the glasses and the sides of the holders 12 are adapted to be spread or contracted properly to conform to the glasses or tumblers so that they will be held against undue movement in the holders.

Where the rack is square, rectangular, octagonal, or of other polygonal form, the glass hold-

ers 12 may be arranged along and secured to the sides of the base, and in the case, for instance, of an oval or other form of rack, the holders may be appropriately arranged about and secured to the base thereof.

The construction and design of the handle for the rack may vary widely within the scope of the present invention. The particular handle selected for illustration is a wire handle 40 having a generally looped handle part disposed above the axis of the rack, and the diverging lower ends of the intersecting portions of the handle extend out laterally at 41. The outer ends of these laterally extending portions 41 are turned to lie parallel to the base of the rack in position across the bottoms of the base rings 10 and 11, and are welded to the wire base rings 10 and 11 at 42.

The individual tumbler holder 12a shown in Figures 6 and 7 is similar to the holders 12 of the previous embodiment of the invention except that instead of having the sides or legs of the U contracted, these sides are arranged in intersecting relation—that is, with one crossing the other at 14a. This crossing or intersection of the legs of the U provides the desired retention for preventing displacement of the glass when the holder is rolled or otherwise brought to form. The free ends of the U-shaped holder 12a are indicated at 18a in Figure 7 and are welded to the base rings indicated at 10a in the manner of the previous embodiment of the invention.

I do not intend to be limited to the precise details shown or described.

I claim:

1. A tumbler rack comprising a base, a plurality of individual wire tumbler holders of generally U-shaped form with the free ends of the legs of the U-shaped holders disposed generally horizontally across said base and welded thereto, the bights at the upper ends of said U-shaped holders being formed to positions substantially parallel to said base and substantially parallel to the free ends of the legs of said holders and spaced upwardly above the base to receive tumblers, and the portions of said holders intermediate said bights and the generally horizontally disposed free ends of the legs of the holders being bowed inwardly to form contracted portions intermediate said bights and the base of the rack for holding the tumblers against sidewise displacement from said holders.

2. A tumbler rack comprising a base, a plurality of individual wire tumbler holders of generally U-shaped form with the free ends of the legs of the U-shaped holders disposed generally horizontally across said base and welded thereto, the bights at the upper ends of said U-shaped holders being formed to positions substantially parallel to said base and substantially parallel to the free ends of the legs of said holders and spaced upwardly above the base to receive tumblers, and the portions of said holders intermediate said bights and the generally horizontally disposed free ends of the legs of the holders being of continuous inwardly bowed curvature from the outer ends of the generally horizontally disposed free ends of said legs to the bights at the upper ends of the holders to form contracted portions intermediate said bights and the base of the rack for holding the tumblers against sidewise displacement from said holders.

ADOLPH J. HAVLIS.
